UNITED STATES PATENT OFFICE

RAY H. FITZ GERALD, OF BIRMINGHAM, ALABAMA

CARTON

Application filed November 22, 1928. Serial No. 321,129.

This invention relates to improvements in cartons and more particularly such as are made of cardboard or the like and so folded as to provide compartments to receive eggs,—
5 one object of the invention being to so construct the carton as to provide means to hold the eggs in a manner to minimize the danger of breakage.

With this and other objects in view, the invention consists in certain novel features as hereinafter set forth and pointed out in the claims.

In the accompanying drawings:—

Figure 1 is a view of the blank from which 15 the carton is made;

Figure 2 is a perspective view of a carton formed by folding the blank shown in Figure 1;

Figure 3 is a perspective view showing the 20 carton open for the reception of eggs;

Figure 4 is a longitudinal sectional view of the device, and

Figure 5 is a transverse sectional view.

The cardboard blank shown in Figure 1 is scored for folding on the lines 1, 2, 3, 4, 5, 6, 7, 8, 9, 10, 11, 12 and 12^a—the panel 13 between the score lines 5 and 6 constituting the bottom of the carton and the panel 14 between the score lines 8 and 9 providing the 30 top of the carton, and the score line 7 provides a hinge between the bottom and top sections of the carton. That portion of the blank between the score lines 3 and 4 is cut to form a plurality of pairs of resilient flaps 15, the flaps of each pair being disposed opposite each other to receive two eggs between them. The flaps 15 are hinged directly together in pairs, as at 30 and the various connected flaps are united with the edges of the 40 side walls of the section by means of angle members 31—one flap of each pair of connected flaps being cut as at 32 to form the angle member 31. The cooperating flaps of each pair are notched as at 17 and the edge portion of a panel 17^a at the upper end of the blank is provided with tongues 18^a and shorter beveled tongues 19. When the blank is folded on the score lines 8, 9, 10, 11, 12 and 12^a with the panels between the score lines 11 and 12 and the score lines 7 and 8 lying against each other and secured by staples 24 or other suitable fastening means, a box-like upper section 25 is formed and into which the resilient flaps 26 may be caused to project—the tongues 18^a projecting through the notches 17^b while the beveled tongues 19^a will receive 50 the central portions of the flaps 26.

At the center of the upper section 25 of the carton, two flaps 26 are omitted, and a fastening flap 28 is formed on one edge of the panel between the score lines 9 and 10. This flap 28 is adapted to be bent between its ends, as shown in Figs. 2, 3 and 5 and the end member 28^a of said flap is passed through a slot 29 near one edge of the panel 13 of the sections, when the sections of the carton are 60 folded one upon the other as shown in Figure 2, thus effectually connecting the sections and preventing their accidental separation.

The tongues 19 and 18^a serve as partitions separating two eggs which may be placed be- 70

100

ween each pair of flaps of the respective sections of the carton. When the sections are closed one upon the other, the tongues 18 of the lower section will lie parallel with the tongues 18^a of the upper section and enter the notches 17^a in flaps 26 of the upper section and the tongues 18^a of the upper section will enter notches 17 of flaps 15 of the lower section.

10 It will be observed that the carton comprises two box-like sections hinged together and that with my improvements, the eggs will be supported out of actual contact with the bottom and top walls 13 and 14 of the carton 15 and that they will be supported in a resilient manner within the carton so that liability of breakage during storing or handling of the filled cartons will be reduced to a minimum.

Having fully described my invention what 20 I claim as new and desire to secure by Letters-Patent, is:—

1. A carton of the character described comprising bottom and top sections foldable one upon the other, each of said sections having a plurality of pairs of resilient flaps, each pair of flaps adapted to engage an article disposed between them, the flaps of the bottom section having notches, and a longitudinally extending member in the bottom section 25 having tongues passing through the notches of the flaps therein and forming partitions. 90

2. A carton of the character described, comprising bottom and top sections foldable one upon the other, each of said sections having a plurality of pairs of resilient flaps, each pair of flaps adapted to engage an article disposed between them, the flaps of both the bottom and top sections having notches, and a longitudinally extending member in each 30 of said sections having tongues passing through the notches of the flaps of both sections and forming partitions. 100

3. A carton of the character described comprising bottom and top sections foldable one upon the other, each of said sections having a plurality of pairs of resilient flaps, each pair of flaps adapted to engage an article disposed between them, said flaps having notches, and a longitudinally extending member in each 45 section having tongues passing through the notches of the flaps therein and forming partitions, said longitudinally extending members also having shorter tongues engageable between adjacent flaps. 110

5. A carton of the character described comprising bottom and top sections foldable one upon the other and each of said sections having a plurality of pairs of cooperating flaps, said flaps being hinged directly together in pairs, an angle member integral with each pair of connected flaps and integral with the side walls of the sections respectively, the flaps of the respective sections having notches, and tongues forming partitions en- 125

tering the notches in the flaps of the respective sections.

5. A carton of the character described comprising bottom and top sections foldable one upon the other and each of said sections having a plurality of pairs of cooperating flaps, said flaps being hinged directly together in pairs, an angle member integral with each pair of connected flaps and integral with the side walls of the sections respectively, the flaps of the respective sections having notches, tongues forming partitions entering the notches in the flaps of the respective sections, and beveled tongues to receive central portions of hinged flaps of the upper section. 70 75 80

In testimony whereof, I have signed this specification.

RAY H. FITZ GERALD.
